REIGNITER FOR AUTOMOBILE HEATERS

Filed Nov. 29, 1937

UNITED STATES PATENT OFFICE

2,192,688

REIGNITER FOR AUTOMOBILE HEATERS

Henry J. De N. McCollum, Evanston, Ill.

Application November 29, 1937, Serial No. 177,078

2 Claims. (Cl. 158—28)

My invention relates generally to automobile heaters of the internal combustion type and more particularly to reigniters for use in heaters of this type.

5 In heaters of the general type disclosed in my co-pending application Serial No. 61,213, filed January 28, 1936, difficulty was occasionally experienced in the operation of the heater due to the fact that the reigniter plug therein failed 10 to function under certain conditions of operation. For example, the heater might be started in the usual manner and operate a sufficient length of time to cause the thermostatically controlled switch to disconnect the electrical igniter 15 from the source of current prior to the time that the reigniter plug had been raised to a sufficient temperature to cause reignition of the combustible mixture in the combustion chamber. This 20 might occur if the flame in the combustion chamber became extinguished due to an unusual and sudden decrease in the intake manifold vacuum. Under such circumstances, the flame might remain extinguished for a short period until the heater became cooled sufficiently again to cause 25 the thermostatically controlled switch to close the circuit to the electrical igniter. Such operation had the disadvantage that the heater was temporarily ineffective to heat the passenger 30 compartment of the vehicle and also because of the additional undesirable drain upon the automobile battery due to the second operation of the electrical igniter.

It is therefore an object of my present invention to provide an improved reigniter plug which 35 is effective to maintain combustion in the combustion chamber after being heated for a relatively short interval of time.

A further object is to provide an improved reigniter for heaters of the internal combustion type in which the shape of the reigniter is such that it is rapidly raised to its effective ignition 40 temperature.

Other objects will appear from the following description, reference being had to the accompanying drawing, in which:

Fig. 1 is a fragmentary sectional view of an automobile heater incorporating the improved reigniter plug of the present invention; and

Fig. 2 is a transverse sectional view taken on the line 2—2 of Fig. 1, showing the reigniter plug in elevation.

In order that the improved operating characteristics of the reigniter plug may be more readily understood, the description thereof will be

preceded by a brief general description of the heater in which it is incorporated.

The heater comprises generally a casting 10 having a combustion chamber 12 formed therein and to which a combustible mixture of liquid fuel (gasoline) and air is supplied through a tube 14 from a carbureting device 16, the latter being supplied with liquid fuel through a conduit 18 which is connected to receive fuel from the fuel supply system of the automobile in which the heater is installed, herein shown as connected to the float bowl 20 of the engine carburetor.

The combustible mixture of air and fuel supplied to the combustion chamber 12 is raised to its kindling temperature by an electrical igniter 22 which is generally in the form of a high resistance nichrome wire. The products of combustion flow past the reigniter plug 24, herein-after to be described in detail, and thence through circuitous passageways formed in a radiator core 26 which is surrounded by a shell 27 and heat radiating fins 28. A Venturi type nozzle 30 is positioned at the end of the circuitous passageway formed in the radiator core 26, and is connected by a passageway 32 with a conduit 34 leading to the intake manifold 36 of the engine of the automobile upon which the heater is mounted.

The operation of the heater is controlled by means of a knob 38 secured to a rod 40, which, at its end, has a valve 42 engageable with the mouth of the Venturi type nozzle 30 to cut off flow of gases through the heater. The control knob 38 also serves as a means for operating a pair of switches 44, 46, which respectively control the flow of current to a motor 48 which drives a fan 50, and control the flow of current to the electrical igniter 22. The operation of this switch is such that when the control knob 38 is pulled outwardly to initiate operation of the heater, the switch 46 will close first and cause the electrical igniter 22 to be supplied with heater current. The electrical igniter having

ignited the combustible mixture which is drawn through the carbureting device 16 by the intake manifold suction, the heat of combustion raises the temperature of the radiator core 26 and its associated shell 27 to a high temperature, the heat being also transmitted to a bimetal thermostatic actuator 52, the lower end of which moves to the left as the element becomes heated. In this manner, the contacts of the switch 46 will first be opened as the heater attains its substantially normal operating temperature. Shortly thereafter, with a slight increase in the tem- 55

perature of the thermostatic element 52, the latter will close the contact switch 44, and thus the fan 50 will be operated to circulate air from the passenger compartment of the vehicle past the radiator 26, 27, 28.

5 The reigniter plug 24 is made of a ceramic material having a relatively thick central portion 54 provided with a cylindrical recess 56 and a plurality of concentrically arranged perforations 58 which form passageways for the flow of the products of combustion from the combustion chamber 12 to the passageway in the radiator core. Alternate perforations 58 are intercepted by slots 60 extending radially inwardly from the edge of the plug. These slots are provided to allow for the expansion and contraction of the plug with changes in temperature.

Upon initiation of the operation of the heater, the hot gases of combustion will surround and 20 impinge against the surface of the reigniter plug, and rapidly heat the latter. The central portion of the plug is in effect thermally insulated from the walls of the combustion chamber so that this portion of the plug will rapidly be 25 raised to the temperature of incandescence at which it is capable of reigniting the combustible mixture should the flame become extinguished accidentally. The central portion 54 of the plug provides a sufficient heat retaining mass around 30 the recess 56 so that the walls of said recess will be maintained at an ignition temperature for a considerable length of time. Thus, under adverse conditions of engine operation, when the intake manifold vacuum fluctuates greatly, the 35 reignition plug will maintain its ignition temperature during the periods when the intake manifold vacuum is insufficient to maintain the flow of combustible mixture into the combustion chamber at the rate sufficient to maintain proper 40 combustion. The reigniter plug will, during these periods, cause ignition of such of the combustible mixture as is drawn into the combustion chamber even though the rate at which it flows is insufficient to maintain a steady flame, and 45 unless the period of insufficient intake manifold vacuum is excessively extended, the reigniter will cause reignition and resumption of steady operation as soon as the intake manifold vacuum is sufficient to cause flow through the heater at 50 a normal rate.

The reigniter plug 24, due to its improved shape, will heat up so rapidly that it will have attained incandescence or at least a temperature sufficient to ignite the combustible mixture prior 55 to the time that the thermostatic element 52 opens the electrical igniter control switch 46. Thus, during the initial starting period, the combustion will be maintained in the first instance by the electrical igniter, for a short period by 60 both the electrical igniter and the reigniter plug, and thereafter, solely by the reigniter plug. As

a result, there is but a very slight possibility that the flame in the combustion chamber will become extinguished due to extended erratic variations in the degree of intake manifold vacuum, and the possibility that the electrical igniter will be 5 energized more than once substantially eliminated.

Of course, if the operator of the vehicle permits the engine to remain stopped for an extended period, the reigniter plug may cool sufficiently 10 to necessitate reenergization of the electrical igniter, but with the improved reigniter disclosed herein, the possibility that the intake manifold suction will be reduced for such an extended period during regular operation of the vehicle is 15 so small as to be negligible.

While I have shown and described a particular form of reigniter, it will be apparent to those skilled in the art that variations and modifications thereof may be made without departing 20 from the essential features of my invention set forth in the accompanying claims. I therefore desire, by these claims to include as my invention all such modifications and variations by which substantially the same results are secured 25 in substantially the same way.

I claim:

1. In an automobile heater of the internal combustion type, a combustion chamber, means to supply a combustible mixture to said chamber, 30 electrical means for igniting the mixture in said chamber, means responsive to the temperature of the products of combustion flowing from said chamber to deenergize said electrical igniter, and a reigniter forming a wall of said combustion chamber and having a central portion of greater thickness than the edge portion thereof, said central portion projecting into said combustion chamber in the path of flow of the burning gases therethrough and having a relatively deep recess formed therein, said recess opening into said combustion chamber.

2. In a heating apparatus in which a combustible mixture of fuel and air is supplied to a combustion chamber and the products of combustion 45 are drawn from the combustion chamber through a heat transfer device by a source of suction which may occasionally fail, a reigniter plug adapted for location between the combustion chamber and the heat exchange device to reignite 50 the combustible mixture after a short failure of said source of suction, said plug being of a ceramic material and having a plurality of generally cylindrical passageways extending therethrough, said passageways being spaced a short 55 distance from the periphery of the plug and at least some of said passageways having communicating slots extending to the periphery of the plug, said plug having a central recess formed in one side thereof.

HENRY J. DE N. McCOLLUM.
